UNITED STATES PATENT OFFICE.

BUNJIRO OTA, OF PARADISE, MONTANA.

DESIGN FOR AN INKSTAND.

46,856.

Specification for Design.

Patented Jan. 12, 1915.

Application filed October 29, 1914. Serial No. 869,324. Term of patent 14 years.

To all whom it may concern:

Be it known that I, BUNJIRO OTA, a subject of the Emperor of Japan, residing in the city of Paradise, in the county of Saunders and State of Montana, have invented a new, original, and ornamental Design for an Inkstand, of which the following is a specification, reference being had to the accompanying drawing, forming part thereof.

The figure is a perspective view of an ink stand, showing my new design.

I claim—

The ornamental design for an ink stand, as shown.

BUNJIRO OTA.

Witnesses:

K. KOIKE,

HARRISON M. BROOKS.
